UNITED STATES PATENT OFFICE.

DAVID HUMPHREYS, OF NORFOLK, VIRGINIA.

SELF-CLOSING HATCHWAY.

SPECIFICATION forming part of Letters Patent No. 274,777, dated March 27, 1883.

Application filed December 21, 1882. (No model.)

To all whom it may concern:

Be it known that I, DAVID HUMPHREYS, a citizen of the United States, resident at Norfolk, in the county of Norfolk and State of Virginia, have invented certain new and useful Improvements in Self-Closing Hatchways; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a vertical section of this invention. Fig. 2 is a horizontal section. Fig. 3 is a vertical section showing the hatchway closed. Fig. 4 is a vertical section showing the hatchway open.

This invention has relation to self-closing hatchways for elevators; and it consists in the construction and novel arrangement, in connection with the elevator-uprights, and horizontal hatchway-slides reciprocating at right angles to the plane thereof, of the pairs of bent levers pivoted to the elevator-uprights on each side of the elevator-way and above and below the hatchway-flooring, the rods connecting the bent levers to the hatchway-slides, and the double bearings of the elevator car or platform, adapted to receive the arms of the pairs of bent levers, as hereinafter set forth.

In the annexed drawings, the letter A designates a hatchway or opening made in a floor, B, of a building for the passage of the elevator car or platform C.

D are the uprights of the elevator-way, centrally arranged on each side of the hatchway, and provided with the usual metallic guides, E, for the car. Between each guide E and the upright D, back of the same, is arranged a slotway, g, above as well as below the hatchway-flooring; or the slotway g may be formed in the guide or in the upright. In each slotway g is pivoted a pair of bent levers, L L, each lever being centrally pivoted, as indicated at h, and having an upper oblique arm, k, and a lower oblique arm, l, said arms being reversely curved at their terminal ends, as represented at m.

S S represent the hatchway-slides, which re-

ciprocate toward and from each other, their edges n meeting in a line between the elevator-uprights, so that they completely close the hatchway, forming a perfect bar to any draft through the elevator-way, and therefore serving to prevent the spread of fire by the elevator-way. These slides S S are designed to move in the direction at right angles to the plane of the elevator-uprights, so that there will be no necessity of slotting them to provide for said uprights.

To each side of each slide S is hinged, at t, a connecting-rod, R, which extends obliquely through the slotway g, and is pivoted to the lower end of the lower arm of the opposite lever L of the pair which are pivoted in said slotway.

To the under side of each slide S, on each side thereof, is hinged a similar connecting-rod, R', which passes through the lower slotway g, and is pivoted to the upper arm of the lever on the opposite side, below the hatchway.

The sides of the car C are provided with bearings V V', which are arranged in pairs or double, one pair being placed higher than the other on the same side, as indicated in the drawings. Roller-bearings v are preferred, and those composing each pair are separated horizontally, the interval between them being sufficient to receive the ends of a pair of bent levers when in the closed position, as indicated at z.

It will be observed that the arms of each pair of levers which are in the closed position cross each other near their reversely-curved ends, so that the latter are turned inward to engage the bearings by their convex edges.

When the car approaches the hatchway from below, the double bearings pass on each side of the bent levers, the lower arms of which are closed toward each other, and said bearings engage the upper arms of said levers, which are in the extended position, the hatchway being closed. As the car rises, the arms k of the lower levers are forced toward each other by the double bearings V, and this movement, being communicated to the hatchway-slides by the rods R, separates them and opens the hatchway for the passage of the car. When the car rises from the hatchway its double bearings engage the upper arms, k, of the upper levers L and force them together, thereby extending

the lower arms, *l*, of said levers and closing the hatchway-slides. In the descent of the car, the lower double bearings, *V'*, serve to close the lower arms, *l*, of the upper levers, 5 forcing the hatchway-slides apart. As the car descends from the hatchway the double bearings *V* engage the extended lower arms of the lower levers, forcing the hatchway-slides together.

10 I am aware that bent levers are not new in the construction of self-closing hatchways, and I do not broadly claim such devices.

What I claim, and desire to secure by Letters Patent, is—

15 1. The combination, with the hatchway-slides reciprocating horizontally toward each other, of the slotways *g*, extending vertically above and below the flooring, the pairs of bent levers *L L*, pivoted in said slotways on each 20 side of the elevator-way, the connecting-rods *R*, extending from the slides, respectively, to the opposite bent levers, and the double bearings on the car, substantially as specified.

2. The combination, with the horizontally-reciprocating slides *S S* and the bent levers *L L*, arranged in pairs in vertical slotways on each side of the elevator-way, of the oblique connecting-rods *R*, hinged respectively to the slides extending through said slotways and pivoted to said bent levers, substantially as 25 specified.

3. The combination, with the vertical slotways *g*, in or back of the elevator-guides *E*, and the pairs of bent levers *L L*, pivoted therein, of the upper and lower double bearings, *V* 30 *V'*, of the car, extending on each side of the guides, substantially as specified.

4. The bent levers *L L*, having the reversely-curved arms *k l*, substantially as specified.

In testimony whereof I affix my signature in 40 presence of two witnesses.

DAVID HUMPHREYS.
